UNITED STATES PATENT OFFICE.

SAMUEL B. FIELD, OF HOLBROOK, MASSACHUSETTS, ASSIGNOR OF ONE-FOURTH TO PNEUMATIC SCALE CORPORATION, LIMITED, OF QUINCY, MASSACHUSETTS, A CORPORATION OF MAINE, AND THREE-FOURTHS TO WILLIAM H. DOBLE, OF QUINCY, MASSACHUSETTS.

LOCK AND SEAL FOR BOXES.

1,247,251.

Specification of Letters Patent. Patented Nov. 20, 1917.

Application filed December 4, 1916. Serial No. 134,811.

To all whom it may concern:

Be it known that I, SAMUEL B. FIELD, a citizen of the United States, residing at Holbrook, county of Norfolk, State of Massachusetts, have invented a certain new and useful Improvement in Locks and Seals for Boxes, of which the following is a specification, reference being had therein to the accompanying drawings.

10 The invention is especially intended for application to use in connection with shipping cases, especially metal shipping cases, to serve as a tell-tale if the box has been tampered with or opened after it has been locked and sealed. Although it is especially intended for application to use with a shipping case, it is not intended to be limited to use with a box of that character or even to a metal box. As it is especially intended 15 however to be used in connection with metal shipping cases, the invention is shown in the drawings as embodied in a box of that character.

The invention comprises a combination 20 locking and sealing mechanism in which the key serves as a part of the locking mechanism and remains in the lock, and in which after the locking and sealing mechanism have once been assembled it is impossible 25 to unlock the device except by breaking the key. Every time the box is locked a new key has to be employed.

The invention will be fully understood when taken in connection with the accompanying drawings and the novel features 30 thereof will be pointed out and clearly defined in the claims at the close of this specification.

In the drawings, Figure 1 is a plan view 35 of a box embodying the invention.

Fig. 2 is a front elevation of the right hand upper portion of a box embodying the invention, being a front elevation of the parts shown in Fig. 1 and showing the 40 box locked and sealed.

Fig. 3 is a section on line 3—3 of Fig. 2.

Fig. 4 is a section on the same line as Fig. 3 but showing the cover and front panel in the unlocked position and the cover 45 slightly raised.

Fig. 5 is a section on line 5—5 of Fig. 2.

Fig. 6 is a sectional elevation sectioned

on line 6—6 of Fig. 5 showing the key removed.

Fig. 7 is an elevation in detail of the 55 key.

Fig. 8 is a side elevation, broken away, of the key shown in Fig. 7, viewed from the right hand side.

Referring now to the drawings, A represents the front panel, B the cover and C one of the end panels of the box. The cover B is intended to be hinged at its rear edge to the back panel of the box, (not shown) and preferably it is formed with a concave depression or groove 1 on the underside along each edge into which fits the convex upper edge 2 of the panel C as shown in Figs. 2, 3 and 4.

Preferably in the type of box shown in 70 the drawings, the cover and each panel is formed of inner and outer wall plates 3, 4 spaced apart from each other, and the edge of each panel is formed by a channel plate inserted in the space between the inner and outer wall plates. For instance, the front panel A has a channel plate 5 which is fitted and secured between the inner and outer plates 3, 4, and has an upwardly projecting rounded portion 2 formed by the fold of the 75 plate. The cover has the inner and outer plates 6, 7, and has a channel plate 8 at the front edge, the inner plate 6 and the lower face of the channel plate 8 each being formed with a depression which makes the 80 85 concave groove 1.

In the form of box shown, the front panel A has a hinge connection with the two end panels, as indicated in the connection between panels A and C in Fig. 2, but 90 the hinge construction is not shown in detail as it forms no part of the present invention.

Secured to the upper face of the cover B is a plate 9 which forms a part of the lock and which for convenience of short designation will be hereinafter referred to as the cover plate. This cover plate is secured to the outer plate 7 of the cover B by any suitable means, the means shown being rivets 10 which are preferably employed where the shipping case is made of metal. The cover plate is preferably formed with a raised rib portion 11 around the periphery of that

portion of the cover plate which lies on the top face of the cover B, said rib being formed hollow by stamping up out of the metal which forms the cover plate as shown in Figs. 3 and 4. The purpose of this rib will be hereinafter described.

The said cover plate also has a downwardly extending front flange 12 which extends down over the front edge for the full thickness of the cover as shown in Figs. 2, 3 and 4.

Preferably the front contour of this flange 12 has at each end a slanting portion 13 which slants outwardly from the outer end and also has the two intermediate rib portions 14 as shown in Fig. 1. The rib portion 11 on the top, and the front rib portions 14 and slanting portions 13 are for the purpose of strength and also for protecting the locking mechanism by serving as sort of bumpers or deflectors to ward off blows striking against the locking mechanism when one box falls on another or glancing blows strike it from any outside source. Secured to the upper front face of the front panel A is the plate 15, which is herein-after referred to as the keeper, said plate being secured to the front panel A by the sealing plate 16 as will be described. The keeper plate 15 has a three-sided slit 17 formed in its face thereby forming a tongue 18 as shown in Fig. 6. This keeper plate is preferably made of spring metal and the tongue 18 remains normally in an outwardly bent position as shown in Figs. 3 and 4. The plate 15 is preferably formed with two vertical hollow rib portions 19 struck up out of the metal for safeguard purposes to be hereinafter described.

The sealing plate 16 is of a vertical length and of a horizontal width sufficient to cover the front face of the locking plate, and at each side edge it is bent backward at right angles, forming the two rearwardly extending portions 20. Each of these two side portions has wings which are curled into shape of open cylinders to form studs 21 terminating in extensions 24 which are to serve as clenches. Each of the two side portions of the sealing plate is thus formed with two of these hollow studs 21 as shown in Fig. 6. The front panel A is formed with four holes 22 corresponding in relative position to the relative positions of the said tubular studs 21. The said studs 21 are of a length equal to the full thickness of the double wall of the panel A. The sealing plate 16 is formed with the two vertical rib portions 23 to allow for the rib portions 19 of the keeper plate.

It should be mentioned that the riveting means for the sealing plate is made integral with the plate so that it is impossible to destroy the fastening means to remove the plate from the box after the cover has been

sealed without destroying the sealing plate itself. If the plate were fastened on with rivets, as is the cover plate, the rivets could be broken off and the box opened after which the plate could be riveted on again. With the riveting means made integral with the plate, if the plate is removed by destroying the fastening means, it cannot again be attached to the front of the box.

The keeper plate 15 and the sealing plate 16 are both assembled with the front panel A at the same time. Before the parts are thus assembled the flange or clenching portions 24 at the inner ends of the sealing plate 16 extend in alinement with the rearwardly extending portions 20. In assembling the parts, the keeper plate 15 is placed against the inner face of the sealing plate 16 and the studs 21 are all brought into alinement with the respective holes 22 in the panel A, then the said studs are pushed through the said holes 22 and the clencher fingers 24 are also passed through the notches 25 in the edge of the keeper plate and through the hole in the panel A. When they are thus far assembled the clencher fingers 24 are bent back at right angles to the portions 20 and flat against the inner face of the panel A as shown in Fig. 5. This securely locks the plate 15 and the sealing plate 16 together and to the panel. When the parts are thus assembled there is a slight space between the sealing plate 16 and the keeper plate 15 equal to the distance that the lower end of the tongue 18 stands out from the plane of the locking plate 15.

The cover plate 9 is formed with a slit 26 along near its front edge for the purpose of receiving the key which is to be described.

The key consists of a plate somewhat T-shaped as viewed in front elevation and somewhat like an inverted L as viewed in side elevation. It has a vertical portion 27 which forms the stem of the T or of the L and has a top flange portion 28 which as viewed in front elevation is of greater length than the stem portion 27 is wide, that is, it extends not only for the full width of the stem portion 27 but also laterally on each side of it. The stem 27 has a cut out portion 29 and the flange top 28 preferably has two downwardly extending ears 30 one on each side of the stem 27. Preferably also the flange 28 is not exactly at right angles to the stem 27 but forms a slightly acute angle therewith as shown in Fig. 8 and for the purpose to be described. The stem 27 is also formed with vertical rib portions 31 along the side edges spaced apart to correspond to the hollow ribs 19 on the keeper plate, but of a little greater diameter so as to cover said ribs 19.

The object of the ribs 19 on the keeper plate 15 and the ribs 23 on the sealing plate 16

16 is so that the key stem 27 must have similar ribs and thus prevent the use of a flat key which could more easily and quickly be made by a person who wished to tamper 5 with the box.

The tongue 18 on the keeper plate should be substantially the full width of the space between the ribs 31 on the key plate stem 27, and the opening 29 should be of substantially 10 the full width of the space between the ribs 31 so that an entirely flat key of a width to pass down between the ribs 19 could not have an opening 29 of sufficient width to receive the tongue 18 of the keeper plate, as the 15 opening would then extend substantially entirely across the stem of the key and so weaken it as to make the key useless.

The keeper plate 15 and the sealing plate 16 are permanently assembled with the front 20 panel when the box is constructed and form a permanent part of the box.

After the box is filled and it is desired to lock and seal the same, the cover is shut down, then the stem 27 of the key is inserted 25 through the slit 26 along the front edge of the cover and is pushed down between the keeper plate 15 and the sealing plate 16. The ribs 19 of the keeper plate form guides for the ribs 31 of the key, there being sufficient 30 space between the keeper plate and the sealing plate as previously described for the passage of the key. The lower end of the tongue 18 of the keeper plate normally engages the inner face of the sealing plate. 35 As the key is forced down in the space between the keeper plate and the sealing plate, the lower end of the tongue will act as a wedge to force back the said spring tongue 18 into the plane of the body of the keeper 40 plate until the lower edge of the open space 29 of the key passes below the lower end of the tongue 18, whereupon the tongue 18 which will then have been put under tension will snap back through the opening 29 45 and against the inner face of the sealing plate 16 and engage just above the lower edge 32 of the opening 29 in the stem of the key. If any attempt is made to withdraw the key the lower edge 32 of the slot 50 will engage the end of the tongue 18 and serve as a stop to prevent the key from being withdrawn. The only way, therefore, that the key can be pulled out is by breaking the key.

55 As already stated, the flange 28 is preferably made at an acute angle to the stem 27. The purpose of this is so that when the key is first introduced and pushed down into engagement with the locking plate, the 60 lower end of the flange 28 will stand up while the outer edge rests on the face of the cover plate as shown in dotted lines in Fig. 3. In this position the stem 27 will not be down quite far enough for the lower edge 65 22 of the slot 29 to pass below the lower end

of the tongue 18. In order to force the key home so as to bring the lower edge 32 of the notch 29 below the tongue 18, the key must be forced or driven down at the bend between the flange and the stem enough to bring the flange 28 into right angles with the stem 27, thus creating additional tension to hold the tongue firmly in engagement with the keeper plate. The full lines of the flange in Fig. 3 show the key in its 70 complete locking position. It is now impossible to disengage the key without breaking off the flange 28 of the key so that the key can then be pushed down entirely through the space between the keeper and the sealing plate and come out at the bottom. The sealing plate therefore serves as a guard to protect the locking mechanism. It is impossible to insert a tool from either 75 the top or the bottom to release the tongue 80 or to force the key down through the slot between the keeper and the sealing plate before the flange or head is broken off.

What I claim is:

1. Locking mechanism for a covered box, 90 said locking mechanism comprising a keeper plate permanently attached to the outside face of one of the panels of the box adjacent the cover, a guard plate which covers the outer face and sides of said keeper and is 95 permanently secured to the same panel to which the keeper is secured in such manner as to leave an entrance between the keeper and guard at the edge adjacent the cover, the cover being formed with an aperture 100 in alignment with the entrance between the guard and keeper, an independent key which is adapted to be inserted through the aperture in the cover and make interlocking engagement with the keeper, and means whereby after the latch connection is made the key is held against removal.

2. Locking mechanism for a covered box, 110 said locking mechanism comprising a keeper attached to the outer face of one of the panels of the box adjacent the cover, the cover being formed with a projection having a slotted opening forming an entrance to said keeper entirely outside of the box interior, a key which is adapted to be inserted into said opening in the cover and engage with said keeper to lock the cover closed, and means for preventing the withdrawal of the key after its engagement with the keeper.

3. A locking and sealing mechanism for a covered box having a cover with a slotted opening therein, said locking mechanism comprising a key which is adapted to extend through said opening, the key being formed with a head which is adapted to engage with the cover and prevent the key from passing entirely through said opening, an adjacent panel having mechanism with which said key is adapted to engage to lock the said 120 125 130

21. cover and panel together, a guard plate attached to said second panel which covers and prevents access to said locking means, and means integral with the said guard plate by which it is attached to the panel of the box.

22. 4. A locking and sealing device for a covered box comprising a key separate from the box, coöperating means connected with the cover and coöperating means connected with the outer face of one of the panels of the box, said key being adapted to be introduced into engagement with both of said coöperating means to effect a locking engagement between said cover and panel, said locking mechanism being entirely outside of the interior of the box and being so constructed that after being locked, the locking connection can be released only by the destruction of the key.

23. 5. A locking and sealing device for a covered box, said device comprising a plate attached to the cover of the box and having a slotted projection which extends over the front edge of the cover, a keeper plate attached to the outer face of the front panel of the box, a spring tongue projecting from the keeper, sealing plate overlying the keeper and projecting tongue and secured to the front panel, and an independent key having a stem which is adapted to be inserted through the slot in the cover plate, thence down between the keeper and the sealing plate and between the tongue and the sealing plate and having a shoulder which when the key has been pushed down a predetermined distance will engage with the tongue of the keeper in such manner as to prevent the key from then being withdrawn, said key having a head which limits the downward movement of the key.

24. 6. A locking and sealing device for a covered box, said device comprising a plate attached to the cover of the box and having a slotted projection which extends over the front edge of the cover, a keeper plate attached to the front panel of the box, a spring tongue projecting from the keeper, a sealing plate overlying the keeper and projecting tongue, said sealing plate having on the side edges projections in the form of studs which pass through holes in the front panel of the box, and clencher fingers which are bent against the inner face of the panel to secure the sealing plate and keeper to the panel, and a key having a stem which is adapted to be inserted through the slot in the cover plate thence down between the keeper and the sealing plate and between the tongue and the sealing plate and having a shoulder which when the key has been pushed down a predetermined distance will engage with the tongue of the keeper in such manner as to prevent the key from then being withdrawn.

25. 7. A locking and sealing device for a covered box, said device comprising a plate attached to the outside of the cover of the box and having a slotted projection which extends over the front edge of the cover, a keeper plate attached to the outer face of the front panel of the box, a spring tongue projecting downwardly and outwardly from the keeper, a sealing plate overlying the keeper and projecting tongue and having projections which pass through the front panel and secure the sealing plate and keeper to the panel, and a key having a stem which is adapted to be inserted through the slot in the cover plate, thence down between the keeper and the sealing plate and between the tongue and the sealing plate and having a shculder which when the key has been pushed down the predetermined distance will engage with the tongue of the keeper in such manner as to prevent the key from then being withdrawn, said key having a head which limits the downward movement of the key, the locking mechanism being entirely outside of the interior of the box.

26. 8. A locking and sealing device for a covered box, said device comprising a slotted plate attached to the cover of the box and projecting over the front edge of the cover, a keeper and a sealing plate overlying the keeper, said keeper and sealing plate both being secured to the front panel of the box by means of members projecting from the sealing plate, said securing members consisting of studs formed integral with the sealing plate, and clencher fingers integral therewith, and a key which is adapted to be inserted through the slot in the cover plate and extend down between the keeper and sealing plate and make connection with the keeper.

27. 9. A locking and sealing device for a covered box, said device comprising a plate attached to the cover of the box and having a slotted portion which extends over the front edge of the cover, a keeper plate attached to the front panel of the box, a sealing plate overlying the keeper and having on its side edges clencher fingers which pass through the front panel of the box and are clenched on the inner side of said panel, thereby securing the sealing plate and keeper to the panel, and a key having a stem which is adapted to be inserted through the slot in the cover plate and to extend down between the keeper and the sealing plate and make a latch connection with the keeper.

28. 10. A locking and sealing device for a covered box, said device comprising a keeper plate attached to the front panel of the box, a sealing plate overlying and covering the keeper and secured to the front panel of the box and having an entrance between the keeper and sealing plate, the cover being formed with an aperture in alinement with

said entrance between the keeper and sealing plate, and a key having a stem which is adapted to be inserted through the aperture in the cover and to extend down between the keeper and the sealing plate and make a latch connection with the keeper, said key being formed with a laterally extending flange on its upper end which is normally at an acute angle to the stem of the key in such manner that when the key is inserted the said flange must be bent into a greater angle to the stem in order to permit the stem to be forced down far enough for the said stem to make a latch connection with the keeper.

11. A locking and sealing device for a covered box, said device comprising a plate attached to the outside of the cover of the box and projecting over the front edge of the cover, the projecting portion being formed with a key slot, a keeper attached to the front panel of the box, a sealing plate overlying the keeper and secured to the front panel, a key adapted to extend down through the slot in the cover plate and between the keeper and the sealing plate and make a latch connection with the keeper, and means whereby after the latch connection is made the key is held against removal, the cover plate being formed with hollow rib portions around its periphery.

12. A locking and sealing device for a covered box, said device comprising a plate attached to the outside of the cover of the box and projecting over the front edge of the cover, a keeper attached to the front panel of the box, a sealing plate overlying the keeper and secured to the front panel, a key adapted to extend down through the cover plate and between the keeper and the sealing plate and make a latch connection with the keeper, and means whereby after the latch connection is made the key is held against removal, the cover plate being formed with hollow rib portions around its periphery.

13. A locking and sealing device for a covered box, said device comprising a plate attached to the cover of the box and projecting over the front edge of the cover, a keeper attached to the front panel of the box, a sealing plate overlying the keeper and secured to the front panel, a key adapted to extend down through the cover plate and between the keeper and the sealing plate and make a latch connection with the keeper, and means whereby after the latch connection is made the key is held against removal, the cover plate being formed with hollow rib portions around its periphery and having a corrugated front flange which extends down over the front edge of the cover.

14. A locking and sealing device for a covered box, said device comprising a plate attached to the cover of the box and projecting over the front edge of the cover, a keeper attached to the front panel of the box, a sealing plate overlying the keeper and secured to the front panel, a key adapted to extend down through the cover plate and between the keeper and the sealing plate and make a latch connection with the keeper, and means whereby after the latch connection is made the key is held against removal, the cover plate being formed with hollow rib portions around its periphery and having a corrugated front flange which extends down over the front edge of the cover.

15. A locking and sealing device for a covered box, said device comprising a plate attached to the cover of the box and projecting over the front edge of the cover, the front flange of the cover plate being at each end inclined outwardly from the end for some distance toward the middle and having hollow vertical ribs intermediate said two inclined end portions, the sealing plate also having vertical hollow ribs in alignment with said vertical hollow ribs in the front flange of the cover.

16. A locking and sealing device for a covered box, said device comprising a plate attached to the cover of the box and projecting over the front edge of the cover, a keeper attached to the front panel of the box, a sealing plate overlying the keeper and secured to the front panel, a key adapted to extend down through the cover plate and between the keeper and the sealing plate and make a latch connection with the keeper, and means whereby after the latch connection is made the key is held against removal, said key having flange ears which project down over the front edge of the cover.

In testimony whereof I affix my signature.

SAMUEL B. FIELD.
